UNITED STATES PATENT OFFICE.

RUDOLPH C. JENSEN, OF SPRINGWELLS, MICHIGAN.

LEATHER FACING FOR CONE-CLUTCHES.

1,227,151.

Specification of Letters Patent.

Patented May 22, 1917.

Application filed June 26, 1916. Serial No. 105,951.

To all whom it may concern:

Be it known that I, RUDOLPH C. JENSEN, a subject of the King of Denmark, residing at Springwells, in the county of Wayne and State of Michigan, have invented certain new and useful Improvements in Leather Facings for Cone-Clutches, of which the following is a specification, reference being had therein to the accompanying drawings.

10 The invention relates to the manufacture of leather facings, such as are used in friction drive clutches, and it is the object of the invention, first, to lessen the cost, and second, to obtain an improved construction.

15 In the present state of the art, it is usual to provide cone clutches with leather facings which form the friction element. This requires the cutting of a strip of leather of sufficient length to form an annulus when

20 the opposite ends thereof are joined, and on account of the conical form the strip must be cut on a curve. As a consequence, a large piece of leather is required for the forming of the strip and there is more or less waste

25 in cutting. Furthermore, as the thickness of the leather is not absolutely uniform in all portions of the sheet, the strip will not be uniform in cross section.

With my improvement the cost of manufacture is greatly reduced by substituting for a long continuous curved strip cut from leather stock a strip formed from a series of overlapped short pieces of leather that may be cut from scrap. The leather sections may 30 also be arranged in slight angular relation to each other, so as to produce the desired curve in the strip without any waste in cutting.

In the drawings:

40 Figure 1 is a perspective view of a leather annulus embodying my invention;

Fig. 2 is a side elevation of a portion of the strip; and

Fig. 3 is a longitudinal section thereof.

45 A A' A'', etc., are leather sections, which may be cut from scrap, and which are preferably of substantially rectangular form. These sections are assembled in overlapping relation to each other and are secured to-

gether by a suitable adhesive or leather cement. By arranging the sections in slightly angular relation, as indicated in Fig. 2, the strip formed will be longitudinally curved, and when the ends are joined together will result in a conical annulus. One or both sides of the strip may then be trimmed so as to produce a continuous surface, as indicated at B Fig. 3. I prefer, however, to only face one side of the strip in this manner, leaving the working or friction face of the notched form indicated at C, produced by the overlapping ends D of the sections. This will have the advantage of producing a more yielding action when the clutch is in operation, as the leather will be compressed and deflected laterally before attaining the maximum frictional engagement with the coöperating member.

In use, the leather annulus is applied to the clutch, preferably to the male member thereof in the usual manner, while the notched surface will frictionally engage the coöperating clutch member to produce the desired result.

What I claim as my invention is:

1. A clutch facing, comprising an annulus formed of a series of small sections of leather overlapping and secured to each other.

2. A clutch facing, comprising an annulus formed of a series of small sections of leather assembled in overlapping relation and cemented to each other.

3. A clutch facing, comprising an annulus formed of a series of small sections of leather assembled in overlapping relation and secured to each other, the successive sections being in slightly angular relation to produce a curve in the strip and a coning of the annulus.

4. A clutch facing, comprising an annulus formed of a series of small sections of leather assembled in overlapping relation, forming a notched surface constituting a yieldable friction face.

In testimony whereof I affix my signature.

RUDOLPH C. JENSEN.
